(57) **CLAIM**

The ornamental design for a holder for coffee machine capsules as shown and described.

DESCRIPTION

FIG. 1 is a front and left side perspective view of a holder for coffee machine capsules in accordance with my new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a top plan view thereof.

The bottom plan view of the holder for coffee machine capsules is not shown and therefore forms no part of the claimed design.

1 Claim, 6 Drawing Sheets
